The ornamental design for a bicycle rack, as shown and described.

DESCRIPTION

FIG. 1 is a perspective view of the bicycle rack of the present invention;

FIG. 2 is a front elevation view thereof; the rear elevation view being a mirror image thereof;

FIG. 3 is a right side elevation view thereof; the left side elevation view being a mirror image thereof;

FIG. 4 is a top plan view thereof;

FIG. 5 is a bottom plan view thereof; and,

FIG. 6 is a cross-sectional view taken along sectional line 6-6 in FIG. 2.
